UNITED STATES PATENT OFFICE.

CONRAD JOBST, OF TOLEDO, OHIO, ASSIGNOR TO THE TOLEDO AUTOMATIC BRUSH MACHINE CO., OF TOLEDO, OHIO, A CORPORATION OF OHIO.

WORK HOLDER FOR BRUSH MACHINES.

Application filed April 1, 1924. Serial No. 703,375.

The invention relates to manufacture of brushes by automatic machines and has for its primary object the obtaining of a higher output and a better quality in the product.

5 In the present state of the art it is usual to provide automatic brush machines with duplicate work holders, in one of which the brush backs are successively bored, while in the other the tufts are set in a previously 10 bored back. With such constructions the drilling of the hole and setting of the tuft must be performed in the same time interval and the slowing of either operation limits the output of the machine.

15 With the improvements in the construction of tuft setting mechanism the time required for the setting of each tuft has been greatly reduced, so that it is difficult to bore a hole in such interval. This results in imperfect bores and is destructive to the drills which are used, and valuable time is lost in resharpening and replacing such drills.

The present invention overcomes the difficulties by segregating the drilling and tuft setting operations and performing the same in separate machines. Thus the boring may be performed by comparatively slow feeding multiple drills, which will produce a better quality of work without injury to the tools. On the other hand, the tuft setting mechanism is not limited by any other operation, which permits of greatly increasing its speed and output. However, such method is only possible where the holes in the previously bored brush backs are successively exactly registered with the tuft setting mechanism. Such exact registration is secured by the improved construction of work carrier, which forms the subject matter of 20 the present invention. A further improvement is that the work carrier permits engagement and disengagement of the work without interruption of the operation of the machine, so that the tufting mechanism may 25 be continuous in its operation.

In the drawings:

Figure 1 is a longitudinal section partly in elevation of the improved machine;

Figure 2 is a sectional plan view of the 30 same;

Figure 3 is a diagram illustrating a development of the cam.

While the improved work holder may be used in connection with various operations

in the process of brush making, such as drilling the brush backs, setting the tufts, etc., there is specifically described only the construction adapted for use in tuft setting. Essentially the construction comprises a carrier having an endless series of work position devices thereon together with means for intermittently advancing said carrier both rotatively and axially and for securing in each step of advancement exactly predetermined registration. More specifically the machine comprises a floating drum carrier which is axially adjusted step by step into a series of successive positions, is guided during such advancement through a predetermined path and is rotatively advanced in intermediate successive series. This permits of setting the tufts in adjacent rows, which may be either parallel or non-parallel and which may be spaced as predetermined.

As shown in the drawings, A is a suitable base provided with a vertically extending hollow standard B within which is concentrically arranged a vertically adjustable member C. The latter is also preferably hollow, but is provided at its upper end with a head D carrying an upwardly extending spindle E. The member C is guided in its vertical movement, preferably by arranging in the annular space between the same and the hollow standard B a series of spaced pairs of vertically grooved guideways F with balls G arranged therebetween. These restrict the movement of the member C relative to the base A to a non-rotative axial movement.

Surrounding the standard B and journaled thereon is a rotative drum member H which has its upper end fashioned to form a stepped cam H'. This cam is in engagement with a bearing I on the member C, preferably a roller, which is mounted at the outer end of a radially extending pin I' secured in a projecting boss I² on said member C. The arrangement is such that when the member H is rotated, the member C will be raised or lowered step by step through a series of predetermined positions. The steps of the cam H' are of sufficient length to cause the drum carrier M to remain stationary momentarily while the brush back is being operated upon. The member H is revolved through the medium of a bevel gear ring J which is in mesh with the bevel pinion K on

a shaft K'. This shaft as shown is driven from a transversely arranged shaft L through the medium of intermeshing skew gears L'.

6 Rotatively mounted upon the spindle E is a floating work holding member M. This is in the form of a cylinder or drum surrounding the member H and having a head M' at its upper end which is connected with 10 the sleeve M² surrounding the spindle E and having ball or other anti-friction bearings M⁴ therebetween. The member M herein-after referred to as the drum carrier is thus free to revolve upon the spindle, but is frictionally engaged with the rotative member H through the medium of a contact member N shown as a spring-pressed plunger located in a recess in said member H. Thus when not held from movement, the drum carrier 15 M will be frictionally driven with and revolved by the member H. The drum carrier M is divided by a central groove portion O into upper and lower rings O' and O². The upper ring is provided with a series of work 20 engaging devices, each comprising transversely arranged locating shoulders and yieldable clamps. Where, as designed, the work to be held in each clamp is a tooth brush back, the portion O' is vertically 25 grooved to form a series of tapering undercut locating ribs P, while a flange P' in the groove O beneath the portion O' forms a series of locating end bearings. Adjacent to each rib P is a radially inwardly extending 30 groove P² containing a series of radially extending spring fingers P³ for engaging one edge of the tooth brush back and pressing the same towards the next adjacent rib. This construction permits of rapidly inserting 35 the brush backs by a downward movement between the rib P and spring fingers P² until the lower end of the back contacts with the flange P'. When thus engaged the back will be firmly held against the drum 40 and in position for exact registration. Also as the ribs are undercut and the fingers slightly curved, the brush back will be drawn in contact with the drum.

The portion O² of the drum carrier M is 45 formed with a series of vertically extending guideways Q, preferably grooves, and these grooves are arranged in groups vertically opposite each of the brush backs in the retaining clamps. In the forming of tooth 50 brushes it is usual to arrange the tufts in non-parallel rows, being closer to each other at the outer end and spreading apart in the direction of the handle. To produce such 55 rows the guide grooves Q in each group are non-parallel, as indicated at Q', Q² and Q³, so that by successively engaging said guide 60 grooves with a cooperating detent the successive vertical reciprocations of the drum carrier M will be parallel to the respective 65 grooves.

The cooperating detent R is of a wedge-shape form and is yieldably pressed into the grooves Q, being periodically instantaneously withdrawn so as to permit the friction member N to revolve the drum carrier M with the member H. This disengagement being only instantaneous will permit re-engagement of the finger R with the next period of disengagement.

The successive disengagements of the detent R are so timed as to occur at the end of each series of vertical steps formed on the cam H'. This timing mechanism as shown comprises one or more dogs S on the shaft L, which during the rotation of said shaft will periodically press against a bearing S' on a slide S², which carries the detent R. This slide S² engages bearings T in a standard T' on the base A while a spring U serves to yieldably press the slide in a direction counter to its movement by the detent S.

The weight of the drum carrier M is preferably partially counterbalanced by suitable means such as the cord or cable V attached to the member C and passing over a pulley V' and downward to a counterweight V².

In operation the machine is placed in connection with any suitable construction of tuft setting mechanism, the discharge nozzle W of which is in a fixed line registering with one of the holes in one of the brush backs. The mechanism of the tuft setting machine is so timed with the rotation of the shaft L that one tuft is set during each interval of rest intermediate the step-by-step movement of the drum carrier M. Thus the tufts will be set in successive rows in the same brush back and succeeding brush backs, the operation being continuous. The brushes when completed can be easily withdrawn from the holding clamps and new brush backs inserted in place thereof, this being performed while the machine is in continuous operation. Thus the capacity of the tufting machine is greatly increased and no time is wasted for the insertion or removal of the work. Furthermore, exact registration is obtained, this being due: first, to the fact that each brush back is exactly located in its clamping holder; second, the cam for moving the carrier axially is provided with parallel steps with exact intervals therebetween; third, the guides Q, Q' and Q² give exact registration to the successive steps in each row.

One important feature of the construction is the non-positive driving connection for rotatively advancing the drum carriers. This is due to the friction drive produced by the shoe or spring-pressed plunger N and the friction is so limited that the drum may be arrested by the detent R. Such a construction dispenses with means for exactly dividing the movement, but nevertheless secures exact registration.

What I claim as my invention is:

1. In a brush machine, a vertically adjustable journal bearing, a drum carrier mounted on said bearing for rotation about a fixed axis, a cam revoluble about the same axis provided with a series of parallel steps of exactly predetermined spacing comprising alternate series respectively ascending and descending, means for non-positively rotating said carrier, a cam follower connected to said bearing and engaging said cam, a series of parallel work holders on said drum carrier, a stop mounted independently of said carrier and guide means on said carrier cooperating with said stop for exactly predetermining the path of movement of the same during the ascending and descending series of steps.
2. In a brush machine, a vertically adjustable journal bearing, a drum carrier mounted on said bearing for rotation about a fixed axis, a series of parallel work holders on the periphery of said drum carrier adapted for the quick attachment and detachment of the work, a stepped cam concentric with the axis of said carrier for imparting an intermittent step by step axial movement to said bearing and carrier, said steps being alternately in ascending and descending series, a series of guides on said carrier for exactly predetermining the direction of movement during the ascending and descending series of steps, a cooperating member for engaging said guides, means for non-positively rotating said carrier, and means for intermittently disengaging said cooperating means from said guides to permit the rotative advancement of said carrier from one guide to another.
3. In a brush machine, a rotatable drum carrier, a continuously moving friction member continuously engaging said carrier, means engaging said carrier to prevent rotation thereof and means for releasing said first mentioned means whereby said carrier is rotatably adjusted.
4. In a brush machine, a rotatable drum carrier, a series of guideways formed on the periphery of said carrier, a continuously moving friction member continuously engaging said carrier, a detent mounted to engage a guideway on said carrier and means for intermittently withdrawing said detent from said guideway whereby said carrier is rotatively advanced.
5. In a brush machine, the combination with a carrier mounted to be moved in transverse directions, of a continuously moving cam for adjusting said carrier, said cam being provided with a series of parallel steps and intermediate inclines, a follower cooperating with said cam and connected to said carrier to move the latter in one direction when engaging said inclines and to maintain said carrier stationary in exactly predetermined position when engaging said steps, and means for controlling said carrier in the transverse direction along a predetermined path.
6. In a brush machine, the combination with a carrier mounted for both rotative and axial movements, of a cam having a series of steps thereon with intermediate inclines, a cam follower engaging said cam adapted to cooperate therewith to axially move said carrier, means for urging said carrier in one direction, a stop for preventing rotation of said carrier, a series of now parallel guideways on said carrier cooperating with said stop to guide said carrier through a predetermined path during the axial movement thereof, and means for periodically disengaging said stop from its cooperating guideway whereby the next successive guideway on said carrier is engaged.
7. In a brush machine, the combination with a base, of an endless carrier mounted for movement in an endless circuit and also for a transverse movement, the axis of said carrier being at all times fixed relative to said base, a series of brush back holders mounted on said carrier and adapted to receive brush backs having a series of rows of holes therein, means for continuously urging said carrier in one direction of its endless circuit, a series of guideways on said carrier corresponding to the rows in said brush backs, a stop cooperating with said guideways to determine the adjustment of said carrier in its endless circuit, means for axially adjusting said carrier step by step, and means for radially withdrawing said stop from said guideways upon the completion of each row, whereby said carrier is moved into position for the next succeeding row.
8. In a brush machine, the combination with a cylindrical standard, of an axially movable member slideable within said standard and non-rotatably secured thereto, a carrier surrounding said standard and rotatably supported by said axially movable member, means for imparting an intermittent axial movement to said member, and means for rotating said carrier.
9. In a brush machine, the combination with a cylindrical carrier having a series of work holders arranged circumferentially thereof, each adapted to hold a brush back having rows of holes therein, a series of guideways on said carrier corresponding to the rows of holes in each brush and successive brushes, means for imparting a continuous torque to said carrier, a stop adapted to engage said guideways, and means for momentarily withdrawing said stop whereby the next successive guideway is engaged thereby.
10. In a brush machine, a cylindrical standard, a tubular revoluble cam surrounding said standard, a non-rotatable member

axially slidable within said standard, a cam follower carried by said non-rotatable member engaging said cam, a carrier rotatably mounted on said non-rotatable member and adapted to be axially moved therewith, said carrier having a cylindrical portion surrounding said cam, and means for rotating said cam.

11. In a brush machine, the combination 10 with a cylindrical standard, of a tubular revoluble cam surrounding said standard, means for continuously rotating said cam, an axially movable member slidable within said standard and non-rotatably secured thereto, a cam follower carried by said member and engaging said cam, a carrier supported on said axially movable member to move therewith, said carrier being journaled on said member and being provided with a 15 depending annular flange surrounding said cam, non-positive driving means between said cam and said depending flange for imparting a continuous torque to the latter, a series of guides circumferentially spaced 20 on said carrier, and a stop adapted to intermittently engage the successive guides.

12. In a brush machine, the combination 20 with a carrier mounted for axial and rotative movements, of a cylindrical cam journaled concentrically with said carrier and having one end thereof provided with a series of parallel steps and intermediate inclines, a cam follower associated with said carrier and engaging said cam to axially 30 adjust said carrier, means for continuously rotating said cam, and means for rotatably adjusting said carrier.

13. In a brush machine, the combination 40 of a drum carrier, a circumferential series of brush back holders mounted on the periphery of said carrier, a mounting for said carrier constraining the same to axial and rotative movements, means for imparting exactly predetermined axial step-by-step movements to said carrier means independent of the first mentioned means for imparting exactly predetermined rotative step-by-step movements comprising a series of guides on the periphery of said drum carrier extending longitudinally thereof, a detent engaging one of said guides, means for continuously urging said carrier rotatively, and means for momentarily withdrawing said 50 detent from said guide and reengaging the same with the adjacent guide.

14. In a brush machine, the combination 60 with an endless carrier mounted for movement in an endless circuit and also for movement transverse thereto, of a series of brush back holders circumferentially spaced on said endless carrier, a series of guides on said carrier spaced circumferentially thereof each guide extending in a direction exactly corresponding to a row of holes in the brush back pattern, means for imparting a

step-by-step movement to said carrier in a direction transverse to said endless circuit, means for continuously urging said carrier in one direction of its endless circuit, a stop engaging one of said guides throughout the 70 entire step-by-step movement in one direction, and means for momentarily radially withdrawing said stop from said guide and reengaging the same with the adjacent guide after a predetermined number of said step-by-step movements.

15. In a machine for making tooth brushes having a plurality of longitudinally extending non-parallel rows of tufts, the combination 80 of a cylindrical drum, a mounting for said drum constraining the same to axial and rotational movements, a circumferential series of tooth brush holders on the periphery of said drum, said drum being of such large diameter relative to the width of the 85 tooth brush that the tufts in the outer rows extend substantially parallel to each other, means for imparting an axial step-by-step movement to said drum, a circumferential series of longitudinally extending guides 90 also on the periphery of said drum in rigid relation to said tooth brush holders and arranged in groups respectively corresponding to the rows on the tooth brushes in the holders, the guides in each group being non-parallel to each other, non-positive means for continuously urging said drum rotatively, and a detent adapted to successively engage said guides to permit successive rotations of said drum and to further constrain 100 the movement of said drum to the non-parallel paths determined by each guide.

16. In a brush machine, the combination 105 with a frame, of a carrier slidably and rotatably mounted on said frame, a series of brush back holders arranged peripherally of said carrier, means for imparting an axial step-by-step movement to said carrier, a series of peripherally spaced guideways on said carrier extending longitudinally thereof for a distance as great as the total axial movement of said carrier, a member mounted on said frame and engaging one of said guideways, means for imparting a non-positive rotary movement to said carrier, and means for momentarily withdrawing said member from said guideway whereby said carrier is rotatively advanced until said member engages the adjacent guideway.

17. In a brush machine, the combination 120 with a frame, of a drum carrier mounted on said frame for rotative and axial movements, a series of brush back holders disposed circumferentially thereon, a circumferential series of guides on said carrier corresponding to the rows of holes in the brush backs, a detent carried by said frame, means for urging said detent into engagement with one of said guides, means for imparting step-by-step axial movements to said drum 125 130

carrier, means for imparting a torque to said carrier, and means for momentarily withdrawing said detent from said guide radially of said carrier.

5 18. In a brush machine, the combination with a movably mounted brush back holder, of a rotatable cam having a series of parallel stepped portions and intermediate inclines, a cam follower engaging said cam and connected to said holder, and means for continuously rotating said cam, whereby said brush back holder is actuated with a step-by-step movement.

10 19. In a brush machine, the combination with a carrier mounted to be moved in transverse directions, of a rotatable cam for moving said carrier, means for continuously rotating said cam, said cam being provided with a series of parallel steps and intermediate inclines adapted to impart an intermittent movement to said carrier in one direction, a series of peripheral guideways on said carrier and a stop adapted to engage said guideways for guiding said carrier during the movement imparted thereto by said cam.

15 20. In a brush machine, the combination with a frame, of a carrier mounted on said frame for axial and rotative movements, means for urging the carrier rotatively, a series of circumferentially spaced brush back holders on the periphery of said carrier, a series of circumferentially spaced guides on the periphery of said carrier cor-

35 responding to the number of longitudinal rows in the brush backs, each guide extending longitudinally in a direction exactly similar to the corresponding row, a detent on said frame engaging one of said guides, means for imparting a step-by-step 40 axial movement to said carrier, and means for intermittently withdrawing said detent to permit step-by-step rotative advancement from row to row.

45 21. In a brush machine, the combination with a frame, a carrier slidably and rotatably mounted on said frame, a circumferential series of brush back holders on said carrier, means for urging the carrier rotatively, a cam having a series of parallel 50 stepped portions and intermediate inclines, means for continuously rotating said cam, a follower connected to said carrier and cooperating with said cam to impart axial movements to said carrier, a series of circumferentially spaced guides on said carrier corresponding to the rows in the pattern of the brush back, a detent on said frame, means for moving said detent into engagement with one of said guides, and 55 means for momentarily withdrawing said detent from said guide radially of said carrier, whereby the latter is rotatively advanced until said detent engages the next adjacent guide.

60 In testimony whereof I affix my signature.

65 CONRAD JOBST.
